(57) **CLAIM**

We claim the ornamental design for a connector for television receiver, as shown and described.

DESCRIPTION

FIG. 1 is a front perspective view of a connector for television receiver showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a bottom-rear perspective view thereof;

FIG. 9 is a perspective view of the connector for television receiver in which a television receiver is provided in broken lines to illustrate an example environment;

FIG. 10 is an enlarged view of the encircled portion 10 in FIG. 1;

FIG. 11 is an enlarged view of the encircled portion 11 in FIG. 1;

FIG. 12 is an enlarged view of the encircled portion 12 in FIG. 2;

FIG. 13 is an enlarged view of the encircled portion 13 in FIG. 3; and,

FIG. 14 is an enlarged view of the encircled portion 14 in FIG. 7.

The evenly dashed broken lines in FIG. 9 showing a television receiver and stand feature depict environmental subject matter and form no part of the claimed design. All (Continued)

other evenly dashed broken lines in the figures depict portions of the connector for television receiver and form no part of the claimed design.

The dot-dash broken lines encircling portions of the claimed design that are illustrated in enlargements form no part of the claimed design.
